UNITED STATES PATENT OFFICE.

HENRY A. WISE WOOD, OF NEW YORK, N. Y., ASSIGNOR, BY MESNE ASSIGNMENTS, TO
WOOD & NATHAN COMPANY, OF NEW YORK, N. Y., A CORPORATION OF NEW YORK.

RELIEF AND INTAGLIO PRINTING PRESS.

1,096,483.

Specification of Letters Patent.

Patented May 12, 1914.

Application filed December 27, 1906, Serial No. 349,717. Renewed August 25, 1911. Serial No. 646,036.

To all whom it may concern:

Be it known that I, HENRY A. WISE Wood, a citizen of the United States, residing at New York, in the county of New York and State of New York, have invented a new and useful Relief and Intaglio Printing Press, of which the following is a specification.

This invention relates to a printing system in which relief and intaglio printing can be done in the same machine preferably substantially simultaneously.

As is well-known, intaglio printing has positive advantages for work which requires great depth of color with much variety of tone and minute gradations of the same, but by that process letter-press work is impractical, so letter-press work is usually done by the relief process, but the results to be obtained by intaglio printing are beyond its capabilities.

To provide a practical and efficient way of combining the excellencies of both systems of printing is the principal aim of this invention. To accomplish this result an intaglio printing member may be caused to work directly in contact with an impression member of a relief press, the impression member receiving impressions first from one printing member and then from the other.

In rotary presses, the impression and relief cylinders are preferably made of the same diameter and the intaglio cylinder either of the same diameter or smaller so that the circumferences of the impression and relief cylinders are a multiple of that of the intaglio cylinder. The intaglio cylinder is interchangeable so that the full sized or the smaller one may be put into position; consequently, its ink fountain is made adjustable and preferably removable so that it can be used with either sized cylinders.

For the purpose of compensating for differences in diameter of the intaglio cylinder due to the taking off of the surface to enable it to receive successive etchings or engravings, means is provided for permitting a circumferential yielding of this cylinder or of the impression cylinder. A construction is also provided to cause the last printed side of the web, which is usually handsomely illustrated, to run in such a way as to not come into contact with the turning roll or the roll at the head of the former.

This invention is designed to accomplish

all these objects and secure these advantages and further ones which will appear hereinafter.

Reference is to be had to the accompanying two sheets of drawings which constitute a part of this specification, and illustrate practical ways of carrying out the inventions and in which—

Figure 1 is a longitudinal sectional view of a rotary web press supplied with intaglio printing cylinders, in accordance with this invention. Figs. 2 and 3 are similar views showing methods of carrying out the invention on presses of a somewhat different type. Fig. 4 is a front elevation of an impression and coöperating intaglio cylinder. Figs. 5 and 6 are sectional views of the same on the line 6 of Fig. 4, and Fig. 7 is a sectional view of the same on the line 7 of Fig. 4.

In newspaper presses the cylinders are adapted to take two plates circumferentially, these plates usually being duplicates of each other, so that when various webs from the same press are associated, each section cut therefrom will represent a paper which is in every respect similar to the one ahead, and to the one behind it. But printing press folders are so arranged that the circumferential product of a cylinder may be collected if need be so that the pages printed by one circumferential half of the cylinder may be imposed upon the pages printed by the other circumferential half of the same cylinder, thus making a product of double the number of pages. By the first plan it is necessary to repeat illustrations when used upon each circumferential half of the plate cylinders, while by the second plan one set of illustrations may be carried by one half and the other by the other half of the plate cylinder. In order to perform this latter function by the use of the present invention, the intaglio printing cylinder is made equal in circumference to the relief printing cylinder, each of said cylinders carrying circumferentially two plates or the equivalent thereof. The same design, of course, may be repeated on the intaglio cylinder by having it engraved upon both of the circumferential halves thereof and thus adapt it to duplicate products, but this makes double etching which is slow and expensive. In order to avoid this, the intaglio cylinder may be made of half the circumference of the relief cylinder when the machine is to

be used with a design repeated for both halves. The half size intaglio cylinder, therefore, makes a revolution for each half of the impression cylinder. When it is necessary, however, to print separate designs upon each half a full size intaglio cylinder is put in, but in all cases the circumference of the relief cylinder as well as that of the impression cylinder is substantially a multiple of that of the intaglio cylinder. The intaglio cylinder and its inking and surface cleaning devices are made removable and also adjustable so that when a cylinder of a different size is used, the inking and cleaning arrangements may be properly adjusted to receive and serve it.

Intaglio printing cylinders are made in the form of copper shells, usually about a half inch thick. As the intaglio printing cylinder and the impression cylinder are run together, and must maintain the same surface velocity, they have had to be accurately fixed in diameter. As these copper cylinders are quite expensive and as there is a great loss in remelting them, I have provided means whereby they can be used several times, the etched or engraved surfaces being successively removed and a new design etched or engraved on the smooth surface. This results in a gradual reduction in diameter on the intaglio cylinder which therefore increasingly drags upon the impression cylinder against which it works. While heretofore this has not prevented the repeated use of a cylinder, it has necessitated the abandonment of it with great loss after it has been used three or four times only. For the purpose of reducing this loss and permitting the use of the copper shell a greater number of times, I have provided a yielding connection between either the intaglio cylinder or the impression cylinder and its shaft, whereby the impression cylinder may cause the intaglio cylinder even though greatly reduced in diameter to rotate with it at the same circumferential velocity until a gap in the impression cylinder is reached, when the yielding means will bring the yielding cylinder back into proper position with relation to its shaft. In this way illustrated during each revolution of the impression cylinder, which has two gaps, the printing cylinder will return twice to proper position and almost the entire thickness of the copper shell can be used before it is abandoned.

In order to prevent the last printed side of the web from coming into contact with the turning roll or the roll at the head of the former, the web is taken from the last impression cylinder in a direction contrary to what has usually been the case. Two ink supplies may, of course, be used, each touching its own surface to be supplied, or one that is operable to both; any ordinary

construction of the same being employed to produce this result.

Referring specifically to the drawings, and first to Fig. 1, it will be seen that the rotary web press is arranged so that the illustrations may be printed in intaglio, and the type in relief, as has been stated above. It will be observed that the cylinders *a*, *b*, *c* and *d*, represent the ordinary printing couples of a rotary web press, the inner cylinders being the impression cylinders.

On each of the printing cylinders *a* and *d* are shown two relief printing plates *e* in accordance with the usual construction. Suitable inking mechanism *f* is also indicated. The web passes from the web roll *g* around guide rollers *h* over the impression cylinder *b* in contact with the plates on the printing cylinder *a*, then around the impression cylinder *c* in contact with the plates on the printing cylinder *d* in the usual way, but the relief plates are so constructed that while all the type and other desired portions are in relief as usual, those parts which would ordinarily be provided with a surface for printing illustrations, which it is desired to print in a more artistic way than can be done with relief printing, are left blank, and additional cylinders *k* and *m* are provided on which are mounted intaglio plates or tubes *n* having the desired designs thereon located to register, of course, with the blank spaces on the relief plates. In the form indicated in this figure, each of the intaglio cylinders is of a diameter equal to one-half of that of the relief printing cylinder, and it is, of course, timed to make a complete revolution during a half revolution of the relief cylinder. With this construction the intaglio design will be repeated for the two impressions obtained from the relief plates, and, therefore, there will be two sets of imprints which will have the intaglio portion thereof in duplicate, and which ordinarily will also have the relief in duplicate, as the two relief plates are normally the same.

It is to be noted that the intaglio cylinders are located beneath or at one side of the impression cylinders so that the ink which drips therefrom will not come into contact with the impression cylinders. The intaglio cylinders are supplied with ink from fountains *o* beneath them these fountains being in the present instance provided with rollers *p*, and cleaning blades or other devices *q* being employed in the usual way. The fountains and cleaning devices are mounted below or at one side of the intaglio cylinders so that the fountains will receive the drip therefrom and no ink will be discharged on the impression cylinders. A preferable position is to have the intaglio cylinders below the horizontal diameter of the impression cylinders and their

inking devices below the horizontal diameters of the intaglio cylinders.

In order that each of the intaglio cylinders k may be replaced by a cylinder of a different diameter, the fountains o are made adjustable and with them the rolls p and cleaning devices q . As shown in Fig. 1, they are mounted on a frame r and can be moved up and down in slots s therein. This figure shows these parts in dotted lines in position to receive a larger intaglio cylinder k' . Also in this figure, it will be seen that the web passes over the roll h' to the left in order that its last printed side, which is usually handsomely illustrated, will be on the outside and when run over the former will not have to come in contact with the roll at the head thereof or with the turning roll, thus better preserving the effect of the printing on this side of the sheet.

In the construction represented in Fig. 2, an ordinary type of press is provided with a single intaglio cylinder k' so that the illustrations will appear on one side of the sheet only. When the circumferential product of the plate cylinder is to be collected as shown the intaglio cylinder k' is made equal in diameter to the plate cylinder a so that a separate set of illustrations may be printed upon each half of the cylinder. The cylinder k' is shown as provided with printing tube n' having two intaglio designs thereon. In Fig. 3 is illustrated another type of press in which a half sized intaglio cylinder k is shown in connection with an impression cylinder b and in connection with an impression cylinder c is shown a full sized intaglio cylinder k' . It may be considered that the change from one size intaglio cylinder to the other is only partly accomplished in the form shown in this figure.

In other forms, and in fact in any form in which the invention may be embodied, it is preferable that the fountain, the intaglio printing cylinder, and its plate all be removable either endwise or sidewise, so that the press may be run without them, and so that they can be changed as may be desired.

Figs. 4, 5, 6 and 7 illustrate the yielding connection between the intaglio cylinder and its shaft. The impression cylinder b is shown in this invention as fixed to its shaft on which is a gear t operating a gear u on a shaft v on which the intaglio cylinder k is loosely mounted. The intaglio cylinder is provided with a lug or stop w adapted to engage a lug or stop x on the gear u and this is the only positive connection between the intaglio cylinder and its gear. A spring v of any desired form yieldingly connects these two elements. Now, it will be seen that while the intaglio cylinder runs in contact with the impression cylinder if it is of a smaller diameter than the impression cyl-

inder, or if the latter is not an exact multiple of the intaglio cylinder on account of the turning down of the surface of the intaglio shell, it will remain in proper registration with the impression cylinder, its lug w gradually drawing away from the lug x . The spring v opposes this action but is not strong enough to prevent it. Now, when a gap z in the impression cylinder comes into such position as to relieve the intaglio cylinder from pressure as shown in Fig. 6, the spring will be free to act to return the intaglio cylinder to such position that the two lugs w and x will again engage and the two cylinders will then be in proper relation with each other, the intaglio cylinder and its gear being in exactly the same relative position as they would be if they were positively connected together. At this time the lugs or stops do form a positive connection between these elements. This will occur twice during each revolution of the impression cylinder and thus permit the use of the cylinder or shell after it has been materially turned down so that it is of much less diameter than it originally was. A similar operation will take place when the impression cylinder is yieldingly mounted instead of the intaglio cylinder. In either case the couple may be driven through the plate cylinder gear, or through the impression cylinder gear.

While I have illustrated and described special forms in which the invention may be embodied, I am aware that it can be practiced in many other ways without departing from the spirit of the invention as expressed in the claims. Therefore, I do not wish to be limited to the particular mechanism shown, or to the particular types of printing presses referred to, but

What I do claim is:—

1. In a rotary web printing press, the combination of a complete impression cylinder, a complete relief printing cylinder of the same diameter adapted to contact therewith, and a complete intaglio printing cylinder arranged to contact with the impression cylinder while the relief printing cylinder is in contact with the impression cylinder, the circumference of the relief printing cylinder being substantially a multiple of that of the intaglio cylinder.

2. In a printing press, the combination of an intaglio printing couple the circumference of one member of which is a multiple of that of the other, with a relief printing member, the circumference of which is the same multiple of that of the intaglio cylinder, said intaglio and relief cylinders being in contact with the impression cylinder at the same time, means for continuously rotating both of the printing cylinders, and means for directing a sheet or web first between the impression cylinder and the intaglio print-

ing cylinder, and then between the impression cylinder and the relief printing cylinder.

3. In a printing press, the combination of 5 a relief cylinder adapted to carry a plurality of relief plates, an impression cylinder, an intaglio cylinder, said relief and intaglio cylinders being adapted to contact with the impression cylinder at the same time, the 10 intaglio cylinder having a circumference equal to half the circumference of the relief cylinder, and means arranged substantially at a lower level than the horizontal diameter 15 of the relief cylinder for supplying the intaglio cylinder with ink.

4. In a printing press, the combination of 20 a relief cylinder adapted to carry a plurality of relief plates, an impression cylinder, an intaglio cylinder, said relief and intaglio cylinders being adapted to contact with the impression cylinder at the same time, the intaglio cylinder having a circumference equal to half the circumference of the relief cylinder, means arranged substantially 25 at a lower level than the horizontal diameter of the relief cylinder for supplying the intaglio cylinder with ink and being arranged below the impression cylinder,

and a cleaning device for the intaglio cylinder.

5. In a printing press, the combination 30 with a relief printing couple of interchangeable intaglio cylinders of different diameters adapted to contact with the impression member thereof and an inking device adjustable toward and from the impression cylinder to 35 accommodate the different intaglio cylinders.

6. In a rotary web printing press, the combination with a relief printing couple, both members of which are complete cylinders of like diameter, of a complete 40 intaglio printing cylinder mounted adjacent to the impression member of said couple, and operating in conjunction therewith, the designs being distributed throughout the 45 surface of the intaglio cylinder, and the relief cylinder having blanks on its surfaces to correspond with the designs on the intaglio cylinder.

In testimony whereof I have hereunto set my hand, in the presence of two subscribing 50 witnesses.

H. A. WISE WOOD.
